Primary Examiner — Kevin K Rudzinski*Assistant Examiner* — Paul D Bohannon(74) *Attorney, Agent, or Firm* — Hanrahan Law Firm
P.A.; Benjamin M. Hanharan(57) **CLAIM**

The ornamental design for a chair, as shown and described.

DESCRIPTION

FIG. 1 is a perspective view illustrating my design for a chair.

FIG. 2 is a left-side view thereof.

FIG. 3 is a front view thereof.

FIG. 4 is a right-side view thereof.

FIG. 5 is a rear view thereof.

FIG. 6 is a top view thereof; and,

FIG. 7 is a bottom view thereof.

The two different stippling patterns shown in the Figures illustrate a contrast in appearance.
